United States Patent Office

Des. 198,135
Patented May 5, 1964

198,135

DOLL

Wilbern T. Segars, 2242 NW. 31st St.,
Oklahoma City, Okla.

Filed July 9, 1962, Ser. No. 70,856

Term of patent 3½ years

(Cl. D34—4)

FIG. 1

The essential features of my design are shown in the full line disclosure on the drawing.

I claim:

The ornamental design for a doll, as shown and described.
